UNITED STATES PATENT OFFICE.

LAFAYETTE PALMER AND ABRAM L. TAYLOR, OF HARRISBURG, PENNSYLVANIA.

HOSE-CLAMP.

1,205,926.

Specification of Letters Patent. Patented Nov. 21, 1916.

Application filed April 26, 1915. Serial No. 23,943.

To all whom it may concern:

Be it known that we, LAFAYETTE PALMER and ABRAM L. TAYLOR, citizens of the United States, residing at Harrisburg, in the county 5 of Dauphin and State of Pennsylvania, have invented new and useful Improvements in Hose-Clamps, of which the following is a specification.

This invention relates to certain novel 10 and useful improvements in hose clamps, and has particular application to a two-part hose clamp.

In carrying out the present invention, it is our purpose to provide a two-part hose 15 clamp wherein the meeting extremities of the sections of the clamp, on the inner surface of such clamp, will be overlapped by tongues formed integral with one of the sections and acting to prevent mutilation of 20 the hose in the application of the clamp, and in which the sections of the clamp may be readily and quickly assembled in clamp formation about the hose and detached from each other when occasion demands.

25 With the above and other objects in view, the invention consists in the construction, combination and arrangement of parts hereinafter set forth in, and falling within the scope of, the claims.

30 In the accompanying drawing; Figure 1 is a cross sectional view through a hose showing our improved clamp applied thereto. Fig. 2 is a collective view showing the parts of the clamp in perspective. Fig. 3 is a 35 longitudinal sectional view through the clamp.

Referring now to the drawing in detail, 1 designates our improved hose clamp as an 40 entirety, such clamp embodying companion semicircular sections 2 and 3 formed of metal. In the present instance, the section 2 is cut out longitudinally as at 4 and formed on one end of the section 2 and projecting laterally therefrom is a lug 5, while 45 formed on the remaining end of the section 2 and projecting laterally therefrom is an ear 6. Formed on one end of the section 3 and projecting outwardly therefrom at an angle thereto is an ear 7 designed to receive 50 the lug 5 on the section 2 whereby a pivotal connection between the sections 2 and 3 is formed, and formed on the remaining end of the section 3 and projecting laterally therefrom is an ear 8 coöperating with the 55 ear 6 and through these alining ears is

passed a securing bolt 9 whereby the sections may be clamped about the hose and held thereon in clamp formation.

In accordance with our invention, the section 3, adjacent to the ear 7, is stamped to 60 form a tongue 10 and this tongue is bent back upon the inner surface of the section 1 and overlies the connection formed by the lug 5 and the ear 7 and extends into the cut out portion 4 of the section 2 and forms, in 65 effect, a continuation of the inner surface of the section 3. Likewise, the section 3 adjacent to the ear 8 is stamped to form a tongue 11 and this tongue 11 is bent back upon the inner surface of the section 3 and forms, in 70 effect, a continuation of the inner surface of the section 3 and overlies the space at the point of contact of the ears 6 and 8. These tongues 10 and 11 engage the hose at 75 diametrically opposite points, as clearly illustrated in Fig. 1, and so prevent pinching of the hose.

To apply the clamp to the hose, it is only necessary to separate the sections and place the lug 5 in the ear 7. The ears 6 and 8 80 are now drawn together by means of the bolt 9, thereby clamping the sections 2 and 3 about the hose. It will be noted that the tongues 10 and 11 engage the hose at the meeting ends of the sections, thereby preventing pinching of the hose, while such 85 tongues form an integral part of one of the sections of the clamp and are held against accidental displacement when the clamp is 90 being applied to the hose or removed therefrom.

We claim:

A hose clamp comprising companion semicircular sections, a lug formed on one end of one of said sections and projecting outwardly therefrom, an ear formed on the corresponding end of the other section and adapted to receive said lug to form a pivotal connection between said sections, ears formed on the remaining ends of said sections and projecting outwardly therefrom, a bolt passed through said ears and adapted to draw said sections together around the hose, one of said sections being stamped adjacent to one end thereof to form a tongue 105 bent back upon such section and overlying the meeting ends of the sections and forming, in effect, a continuation of the inner surfaces of the sections, said section adjacent to the other end being stamped to form 110

a tongue and the last-mentioned tongue being bent back upon the inner surface of the section and forming, in effect, a continuation of the inner surfaces of said sections and spanning the space between the pivoted ends of said sections, said tongues acting to prevent pinching of the hose at the meeting ends of the sections of said clamp.

In testimony whereof we affix our signatures in presence of two witnesses.

LAFAYETTE PALMER.
ABRAM L. TAYLOR.
